C. DE MAURAIGE.

BAYONET.

APPLICATION FILED DEC. 27, 1921.

1,419,961.

Patented June 20, 1922.

INVENTOR
CHARLES. deMAURAGE.

Dr Fletcher Laughlin

UNITED STATES PATENT OFFICE.

CHARLES DE MAURAIGE, OF ST. SIXTE, QUEBEC, CANADA.

BAYONET.

1,419,961.

Specification of Letters Patent. Patented June 20, 1922.

Application filed December 27, 1921. Serial No. 525,222.

To all whom it may concern:

Be it known that CHARLES DE MAURAIGE, a subject of the King of Great Britain, of St. Sixte, in county Labelle, in the Province 5 of Quebec, in the Dominion of Canada, has invented certain new and useful Improvements in Bayonets, of which the following is a specification.

This invention relates to retractile bayonets and has for its objects to provide a bayonet designed to be permanently carried on a gun barrel, to provide a means whereby the bayonet may be readily protruded and subsequently retracted, to provide means to 15 lock the bayonet blade in the protruding and the retracted position.

Further objects are to provide a retractile bayonet which consists of a sheath mounted underneath the gun barrel and within which 20 a blade is slidably mounted to provide a handle slidably mounted on the outer face of the sheath and fastened through the sheath to the blade. To provide a locking means carried by the handle and designed 25 to co-act with the sheath to lock the blade in the retracted and the protruding positions.

Further objects are to provide a retractile bayonet that is simple in construction, not liable to go out of repair and generally adapt 30 the several parts to better perform the functions required of them.

In the drawings:

Figure 1 is a side elevation of a gun barrel, equipped with my improved bayonet in the 35 protruding position.

Figure 2 is a side elevation of the same showing the blade in the retracted position.

Figure 3 is a side elevation of the gun barrel showing the improved bayonet and 40 sheath in longitudinal section.

Figure 4 is a section on the line 4—4, Figure 1.

Figure 5 is a section on the line 5—5, Figure 1.

45 Figure 6 is a section on the line 6—6, Figure 1.

Figure 7 is a perspective view of the locking lever.

Figure 8 is a section on the line 8—8, 50 Figure 3.

In the drawings, like characters of reference indicate corresponding parts in all the figures.

Referring to the drawings:

55 A represents a gun of any ordinary make consisting of a gun barrel 10 which is pro-

vided on its under part with two longitudinally bevelled ribs 11 designed to be engaged by two longitudinally bevelled slots 12 provided on the top part of a cylindrical 60 sheath 17 which may be locked in position by means of the locking pin 14 extending through the ribs 11. The sheath is hollow and its bore is formed in order to match the configuration of the blade which in this case 65 is shown to be formed of three ribs circular in cross section. The sheath is formed underneath with a longitudinal slot 15 as shown in Figures 3 and 4 of the drawings, the purpose of which will be hereafter made 70 clear. The sheath is also provided with two longitudinal slots 16 and 17 designed to engage two corresponding ribs 18 and 19 formed on the inner wall of a cylindrical handle 20 designed to be fastened to a blade 75 21 slidably mounted within the sheath 13 by means of fastening screws 22 extending through the longitudinal slot 15. Obviously, by means of this arrangement the slot 15 provides a clear way for the travel of the 80 screw 22 with which the handle is equipped and when the blade 21 is desired to be protruded the handle 20 is gripped and pushed forward when its ribs 18 and 19 will slide in the corresponding grooves 16 and 17 85 formed on the sheath and the blade 21 will be brought in the position shown in Figure 1 of the drawings. The side of the handle 20 is formed with a longitudinal recess 23 within which is pivotally mounted intermediate of its length as at 24 a lever 25. The lever 25 is formed at one end with the upwardly extending pin 26 which may be knurled on its top face as shown at 27 and the opposite end of the lever 25 is formed 95 with a downwardly extending stud 28 which is designed to engage one of the recesses 29 and 30 formed at each end of the sheath 13. The sheath 13 is provided on its side between the two recesses 29 and 30 with a longitudinal groove 31 within which a small wheel 32 journaled in the lower end of the stud 28 is designed to travel during the operation of retracting or protruding the blade 21. When the several parts of this improved retractile 105 bayonet are to be assembled in order to be mounted on the gun barrel, the blade 21 is slid within the sheath 13 until the threaded bores, provided therein in order to engage the fastening screw 22 of the handle, can be 110 seen through the longitudinal slit 15. The handle 20 in which the locking lever 25 has

already been mounted is then slid over the sheath 13 in order that its two ribs 18 and 19 may come in engagement with the two longitudinal grooves 16 and 17 of the sheath 5 when the screw 22 is placed in position in order to lock the handle to the blade 21. The sheath 13 is then mounted underneath the gun barrel 10 by bringing into engagement the ribs 11 of the gun barrel with the grooves 10 12 of the sheath. The pins 14 are then forced into the transverse bores through the ribs 11 of the gun barrel in order to lock the sheath to the gun barrel. If desired, the pins 14 may be replaced by small screws which may 15 be positioned on each side of the sheath 13 in order to fasten the same to the ribs 11 of the barrel.

When a gun is thus equipped with this retractile bayonet and the blade is to be 20 protruded the handle 20 is gripped in one hand and the pin 26 engaged by the thumb. On downward pressure being exerted against the pin 26 the lever 25 will be pivoted on its fulcrum 24 and the pin 28 brought out 25 of engagement from the recess 30. The handle 20 is then pushed forward so as to cause it to slide on the sheath 13 and thus bring the blade 21 in protruding position above the sheath 13. During this travel of 30 the handle along the sheath 13 the ribs 18 and 19 will slide within the grooves 16 and 17 and the wheel 32 provided on the pin 28 will travel along the groove 31 formed on the side of the sheath 13. When the screws 35 32 come in engagement with the under wall of the sheath 13 at the end of the slit 15 as shown at 33 the forward movement of the blade 21 will thus be stopped. The grip on the handle 20 and on the pin 26 40 being released, the lever 25 will be forced to pivot on its fulcrum 24 by the action of a coil spring 34 provided underneath the pin 26 and bearing against the outer face of the sheath 13. This action of the spring 45 34 will force the pin 28 into engagement with the recess 29 provided at the forward end of the sheath 13 and the blade 21 will thus be locked in the protruding position. In order to withdraw the blade 21 into 50 retracted position the action is reversed and the handle 20 being gripped the pin 26 is depressed in order to disengage the pin 28 from the recess 29 and the handle 20 is pulled back when the blade 21 will be re- 55 tracted within the sheath 13. It is obvious that by means of this arrangement the user of a gun will not have to carry his bayonet blade attached to his belt when the bayonet is not to be used, as by this arrangement the 60 blade 21 is designed to be permanently carried by the gun barrel 10. It is also obvious that by means of this arrangement a bayonet could easily be provided with every gun so that the hunter of big game when in 65 a critical position will have a ready means

of defending himself without the bayonet being a cumbersome arm to carry.

As many changes could be made in the above construction and many widely different embodiments of my invention within 70 the scope of the claims, constructed without departing from the spirit or scope thereof, it is intended that all matter contained in the accompanying specification and drawings shall be interpreted as illustrative and 75 not in a limiting sense.

What I claim as my invention is:

1. A retractile bayonet comprising in combination with a gun a sheath rigidly mounted underneath the gun barrel and 80 formed with a longitudinal slot and longitudinal grooves, a handle formed with ribs slidably mounted in the longitudinal grooves, a screw fastening the handle to the blade extending through the longitudinal 85 slot, and means to lock the blade in protruding and retracted positions.

2. A retractile bayonet comprising in combination with a gun a sheath rigidly mounted underneath the gun barrel and 90 formed with a longitudinal slot and longitudinal grooves, a handle formed with ribs slidably mounted in the longitudinal grooves, a screw fastening the handle to the blade extending through the longitudinal 95 slot, a lever pivotally mounted intermediate of its length in a recess provided in the handle, pins at each end of the lever extending in opposite directions, the pin formed on the lower face of the lever being designed to engage recesses formed at each end of the sheath.

3. A retractile bayonet comprising in combination with a gun barrel a sheath rigidly mounted underneath the gun barrel 105 and formed with a longitudinal slot and longitudinal grooves, a handle formed with ribs slidably mounted in the longitudinal grooves, a screw fastening the handle to the blade and extending through the longitudinal 110 slot, a lever pivotally mounted intermediate of its length in a recess provided in the handle, pins at each end of the lever extending in opposite directions, the pins formed on the lower face of the lever being designed to engage recesses formed at each end of the sheath, and resilient means 115 designed to retain the pins into engagement with one of the recesses.

4. A retractile bayonet comprising in 120 combination with a gun having bevelled ribs formed underneath its barrel, a sheath formed with bevelled grooves designed to engage the ribs, the sheath being further formed with a longitudinal slot, means to 125 secure the sheath onto the bevelled ribs, a blade slidably mounted within the sheath, a handle slidably mounted on the sheath, a screw fastening the handle to the blade and extending through the slot and means to 130

lock the blade in protruding and retracted positions.

5. A retractile bayonet comprising in combination with a gun a sheath rigidly mounted underneath the gun barrel and formed with a longitudinal slot and longitudinal grooves, a handle formed with ribs slidably mounted in the longitudinal grooves, a screw fastening the handle to the 10 blade extending through the longitudinal slot, a lever pivotally mounted intermediate of its length in a recess provided in the handle, pins at each end of the lever

extending in opposite directions, a small wheel journalled in the pin formed on the 15 lower face of the lever, the said pin being designed to engage recesses formed at each end of the sheath and resilient means designed to retain the pin into engagement with one of the recesses.

In witness whereof I have hereunto set my hand in the presence of two witnesses.

CHARLES DE MAURAIGE.
